UNITED STATES PATENT OFFICE

NORMAN B. OBBARD, OF PITTSBURGH, PENNSYLVANIA

ANTICLIMBING DEVICE FOR TOWERS

Application filed August 28, 1931. Serial No. 560,021.

This invention relates to anticlimbing devices for power transmission towers, one of the objects being to provide a means for preventing children from climbing these towers and injuring themselves by contact with the electric high tension lines.

It is characterized by a number of arms which are positioned on the tower to extend both outwardly and inwardly, the outwardly extending arms including a pair of adjacent arms, one of which is arranged for swinging away from and toward the other. Fence wire is stretched between the inwardly extending arms and from the adjacently positioned pair of arms to each of the other outwardly extending arms, so that by swinging the swinging arm a portion of the wire may be slackened to permit passage through the guard of a repairman.

20 In the drawing:

Figure 1 is a top plan view of an example of this invention as it appears applied to a power transmission tower, the tower being shown in cross-section.

25 Figure 2 is a side view of Figure 1.

Having reference to the drawing, there is shown a tower 2 of the type ordinarily used for carrying high tension electric power transmission lines. A plurality of inwardly extending angle iron arms 3 are bolted to each leg of this tower 2, these arms being notched so that barbed wire 4 may be stretched between them and securely positioned by being looped about each arm in these notches. A plurality of outwardly extending angle iron arms 5 are also bolted onto the tower 2 and are likewise notched. Two of these arms 5 are adjacently positioned, one of these being fixed and the other mounted on a hinging bolt 6 for swinging movement, as is indicated by dotted lines and arrows in Figure 1.

Barbed wire 4 is stretched between each of these outwardly extending arms 5 from the two adjacently positioned arms, the wire also being in this instance looped about each arm at its notched part so as to be securely fixed in position. The two adjacently positioned arms are apertured so that a pad lock 7 may be used to lock them together.

50 The above construction adequately pre-

vents climbing of the towers 2 by unauthorized persons, yet when the pad lock 7 is removed and the swingable arm is swung away from the adjacently positioned fixed arm a portion of the barbed wire is slackened sufficiently to permit a workman to climb through the guard and ascend to the top of the tower.

In the example shown the arms 3 and 5 are in each instance oppositely positioned on the tower legs so that they may be fixed thereto by a common bolt 8, thereby saving time and money. In order that the swingable arm may be accommodated to any size tower leg its hinge part is provided with a slot 9 instead of a round hole.

Although a specific form of this invention has been shown in accordance with the patent statutes it is not intended to limit the scope of this invention exactly thereto, except as is defined in the appended claims.

70 I claim:

1. In combination with a power transmission tower, a plurality of extending arms positioned on said tower at spaced intervals, a pair of extending adjacent arms positioned on said tower between two of said first named arms and in a plane therewith, one of these adjacent arms being arranged for swinging movement away from and towards the other and in a plane therewith, and fence wire 75 stretched between said adjacent arms and said first named arms.

2. In combination with a power transmission tower, a plurality of inwardly extending arms, a plurality of outwardly extending arms, two of these arms being adjacently positioned and the others being positioned at spaced intervals therefrom on said tower, one of the two adjacently positioned arms being arranged for swinging movement away 80 from and towards the other and in a plane therewith, means for locking said two adjacently positioned arms together and fence wire 85 stretched from and fixed to said two adjacently positioned arms and said other outwardly extending arms and between said 90 inwardly extending arms.

In testimony whereof, I have hereunto set my hand.

NORMAN B. OBBARD. 100
